UNITED STATES PATENT OFFICE.

ALTON D. HARMON, OF ERIE, PENNSYLVANIA, ASSIGNOR OF ONE-THIRD TO JOHN S. OWEN AND ONE-THIRD TO ANNIE W. S. STRONG, BOTH OF ERIE, PENNSYLVANIA.

COMPUTING-MACHINE.

1,350,727.

Specification of Letters Patent. Patented Aug. 24, 1920.

Application filed February 10, 1919. Serial No. 276,148.

To all whom it may concern:

Be it known that I, ALTON D. HARMON, a citizen of the United States, residing at Erie, in the county of Erie and State of Pennsylvania, have invented certain new and useful Improvements in Computing-Machines; and I do hereby declare the following to be a full, clear, and exact description of the invention, such as will enable others skilled in the art to which it appertains to make and use the same, reference being had to the accompanying drawings, and to the letters of reference marked thereon, forming part of this specification.

This invention relates to calculating machines and consists in certain improvements in the machine for which a patent was issued to me on March 7, 1916, No. 1,174,315, as hereinafter fully described, and claimed.

In the drawings—

Figure 1 is a front view of a calculating machine constructed according to the present invention.

Fig. 2 is a longitudinal section on the line 2—2 in Fig. 1.

Fig. 3 is a like view on the line 3—3 in Fig. 1.

Fig. 4 is a plan view of one of the signal slides of my invention.

Fig. 5 is a view in elevation of one end of the same.

Fig. 6 is a like view of the opposite end of the same.

Fig. 7 is a transverse section on the line 7—7 in Fig. 1.

Fig. 8 is a fragmentary plan view of my invention with a portion of the top plate broken away, and parts of the mechanism removed.

Fig. 9 is a longitudinal section on the line 9—9 in Fig. 8.

Fig. 10 is a plan view of one of the slides of my invention.

Fig. 11 is a section on the line 2—2 in Fig. 1, showing the slide C drawn downwardly to the limit of its movement.

This calculating machine is preferably constructed of thin sheet metal, but other approved material may be used. The front or top plate A is preferably provided with a flange a, along one end and two sides thereof, and the lower edge a' of said flange is turned backward (see Figs. 2, 7 and 9) parallel with the plate A, for the purpose hereinafter set forth.

The plate A is provided with longitudinal slots A', A², A³, A⁴, A⁵, A⁶ and A⁷, equally spaced apart so that the metal between said slots is preferably equal in width to the width of said slots; and along one edge of each of said slots a flange a² is turned downwardly as shown in Figs. 3 and 9. The plate A is also provided with sight-holes a³ substantially in line with the strips of metal between the slots A', A², &c., for the purpose hereinafter set forth.

Upon the perimetrical flanges a' of the front plate A I place a back plate B which contacts with the lower edges of the depending flanges a².

The back plate B is provided with ratchet shaped tooth racks b and b' (see Figs. 2, 3 and 8) under each of the slots in the plate A; the rack teeth b being inclined toward the upper end of the back plate B, and the rack b' toward the lower end of the back plate as indicated in Fig. 8.

Upon the back plate, between each of the depending flanges a² I place duplicate slides C (see Figs. 8 and 10) which slides are held in place in relation to each other by means of said depending flanges a², as shown in Fig. 8.

Each of the slides C is provided with nine notches or holes c which coincide with the racks b in the back plate B, and with nine holes c' which coincide with the racks b' in the back plate B, and are also provided at the upper ends thereof with a ratchet notch c² as shown in Figs. 10 and 11.

Secured to the rear face of the front plate A, parallel with and adjacent to the depending flanges a² are strips of spring metal b² which press downwardly upon each of the slides C to act as a brake to prevent the slides C from being accidentally moved; and between the front plate A and said springs b² I place signal slides D (see Figs. 4 and 8) which are immediately underneath the metal of the front plate between the slots A', A², &c. These signal slides are provided with a projecting portion d and d' at each end thereof; the projection d extending across the slot A' having a portion of the upper edge of the projection d bent 105 downwardly as shown in Fig. 11, so that it will engage the ratchet notch c² at the upper end of the adding slide C when it is drawn downwardly to the limit of its movement, as illustrated in Fig. 11, so as to prevent the 110

slide C from being withdrawn entirely from the machine; and the projections d' being adapted to extend over the adjacent slot A^2 , as is the case with the succeeding slides with 5 relation to the slots A^2 , A^3 , &c.

The slides D are of such length that when the projection d is visible at the upper end of the slots, the projection d' disappears under the plate A at the lower end of the 10 slot.

In order to maintain the signal slide D under the metal of the plate A, between the slots A' , A^2 , &c., said signal slides are provided with downwardly projecting lips d^2 , 15 (see Figs. 5 and 6) which enter the spaces between the slides C.

The action of the springs b^2 tends to press the signal slides D upwardly against the metal of the front plate between the slots 20 A' , A^2 , A^3 , &c., thereby preventing said slides from being accidentally moved. Upon the metal of the front plate, between the slots A' , A^2 , &c., are printed numerals from 1 to 9 inclusive, opposite each of the notches c 25 and upon the slides C are printed numerals from 0 to 9 inclusive, in such position that they will be visible through the sight openings a^3 .

In operation, if it is desirable to add 9 30 and 9, the stylus is placed in notch c of a slide C under slot A' , opposite said numeral printed on the face plate at the left of said slot, and by means of the stylus said slide C is moved downward only until the stylus 35 reaches the lower end of the slot A' ; the stylus when so inserted in said notch extending therethrough and into the ratchet teeth b in the back-plate B thereunder, which permits movement of the stylus in a 40 downward direction only. Then the stylus is inserted in the round hole c' in said slide C showing at the upper end of said slot A' opposite said numeral 9, said stylus projecting therethrough into the ratchet teeth b' in 45 the back-plate B thereunder, which prevents downward movement of the stylus and said slide C. The stylus is then moved upwardly carrying said slide along with it until the stylus reaches the upper end of the slot A' . 50 While moving upwardly in the slot A' the stylus engages the projection d of the signal slide D at the left of the slot A' , which extends across the slot A' and causes the said signal slide to move upwardly thus 55 causing the extension d' on the lower end of the signal slide D to show at the lower end of the next adjacent slot A^2 , and when the stylus stops by reason of its contact with the upper end of the slot A' , the slide C under said slot will show the numeral 8 at the right hand sight opening a^3 . The extension d' on the signal slide D which is now 60 showing at the lower end of the slot A^2 in-

dicates that 1 must be transferred to slide C under that slot. To accomplish this the 65 stylus is mounted in the notch in the slide C under the slot A^2 which is opposite the numeral 1 printed on the face plate at the left of said slot, and by means thereof said slide is moved downward until the stylus contacts with the lower end of the slot A^2 . This causes the extension d' on the signal slide D to disappear at the lower end of the slot A^2 70 and the extension d thereon to reappear at the upper end of the slot A' ; also the adding slide C under the slot A^2 is caused to move downward until the numeral 1 appears at the sight opening a^3 over said adding slide, thus indicating that the sum of 9 plus 9 is 18. 80

The operation of the succeeding slides is identical with that above described. The ratchet shaped rack teeth b and b' in the back plate B are for the purpose of preventing the stylus from being moved in a 85 wrong direction.

It will be noted that the construction of the signal mechanism hereinbefore described is entirely different from that shown and described in my aforesaid Letters Patent; 90 the same being much more simple and requiring a less number of parts, and therefore being more economical in manufacture.

Having thus shown and described my invention so as to enable others to utilize the 95 same, what I claim as new and desire to secure by Letters Patent is:

1. In a calculating machine, a face plate having a slot therein, a back plate, an adding slide between said face and back plates under said slot, a longitudinally movable transfer signal slide between said face plate and said adding slide, an ear on one end of said transfer signal slide extending across said slot and another at the opposite end thereof extending across the next adjacent slot in said face plate, substantially as set forth.

2. In a calculating machine of the class described, a longitudinally movable transfer signal slide, a lateral extension at one end of said slide, an extension at the opposite side of the other end thereof, a down turned ear at each end of said signal slide, substantially as and for the purpose set forth.

3. In a calculating machine, a face plate having a slot therein, a back plate, an adding slide between said plates under said slot, a longitudinally movable transfer signal slide between said face plate and said adding slide, and means on said adding slide to engage said signal slide to limit the downward movement of said adding slide, substantially as set forth.

In testimony whereof I affix my signature. 125
ALTON D. HARMON.
